UNITED STATES PATENT OFFICE.

CHARLES W. LYNCH, OF PERRY, OKLAHOMA, ASSIGNOR TO PICKERING LUMBER COMPANY, OF KANSAS CITY, MISSOURI, A CORPORATION OF DELAWARE.

CORNER PLATE FOR DERRICKS.

Application filed April 9, 1926. Serial No. 100,950.

The object of this invention is to provide a corner plate and box construction for use in connecting the structural elements of a derrick, and especially for connecting the abutting ends of alining leg members and for securing transverse girts to the leg members.

A further object is to provide a corner reinforcing device which shall be adapted for use with angle bar diagonal braces or diagonal bracing rods tensioned by turnbuckles.

A further object is to provide a corner connecting and reinforcing device which shall include inner and outer angle plates positioned to form a box, the corner plates being adapted for connection with wooden girts or with tubular metallic girts, the former being secured to the outer corner plates and the latter being secured to the inner corner plates.

A further object is to provide a particular form of lock between the tubular metallic girts and the corner element or elements.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a view of the construction in side elevation, the view showing a derrick with the corner plates employed in the construction thereof.

Figure 2 is a perspective view, showing the box formed of the inner and outer corner plates, used at the top of the derrick.

Figure 3 is a view in elevation, showing one of the boxes employed at the joints between the leg members, that is, at the joints below the top of the derrick.

Figure 4 is a further view in elevation.

Figure 5 is a section on line 5—5 of Figure 3.

Figure 6 is a detail view showing the edge portion of the flattened end of a tubular metallic girt, of the type illustrated in Figure 3.

Figure 7 shows a modified girt and corner assembly involving the use of the box structure comprising inner and outer angle plates, and adapted for connection with both girts

and tubular metallic girts, having flattened end portions.

In Figure 1, the abutting ends of the legs 55 or leg sections, are assumed to meet centrally of the corner plates, and the elements 10 and 11, in alinement, at the right of Figure 1, therefore meet at about the point indicated by reference number 12, the corner construction of Figures 3, 4 and 5 being employed in this position with reference to the other structural elements of the derrick.

The outer corner plate includes flanges 13, at a right angle with reference to each other, 65 each of these flanges being provided with upper holes 14 and lower holes 15 in which the diagonal braces are secured. Round tie rods 16 have each an end hook portion 17 thereon, and the opposite end portion is 70 threaded at 18 for engagement with a turnbuckle 19. This element last named has threaded engagement with rod or brace 20, and the latter has an upper hook end adapted to engage aperture 21, in the upper corner 75 plate, on the side of the derrick opposite to that on which the corner plate previously described is mounted.

A diagonal brace 21 extends at an angle with brace 20 and has connection with the corner plate positioned opposite the plates already referred to. The central corner plates of Figure 1 may be connected with the corner plates next below by braces 25 and 26, of pipe or angle bar construction, these elements 25 and 26 having flattened ends, apertured, and adapted to be secured by bolts such as 27, to the central angle or corner plates of Figure 1. An additional bolt hole 28 in flange 13 is provided, in order that the same type of plate may be used in other positions on the derrick, and in order that transverse girts requiring several bolt holes may be secured to plates 13, instead of the girt 30, illustrated in the central portion of Figure 1 85 and having connections of the type shown in Figure 3.

The inner angle plate includes the flanges 31 and 32, the latter being cut away, if desired, to provide openings therethru, and this inner angle plate especially includes the cut away portion, or slotted portion, designated 33 providing for the entrance of the extreme end of flattened portion 34 of tubular girt

30, it being understood that this element is a metallic tubular member, as distinguished from the wooden girts referred to elsewhere.

Extending directly from flanges 31 and 32, 5 are threaded devices 37 and 38, constituting pins or bolts adapted to pass thru apertures in the outer corner plate, these pins or bolts 37 and 38 being engaged by nuts 39 bearing on the surface of flanges 13. The inner corner 10 plate is formed of cast metal, and the elements 37 and 38 extend in the plane of the flanges 31 and 32. A rounded surface is provided at 33' for engagement by hook portion 34', and the shoulder 40 initially spaced 15 slightly from flange 13' of the outer plate, in Figure 2, constitutes a vital feature, as it locks the hook end 34' of the girt in position after the latter has been inserted prior to the tightening of the nut 39 on the pin 37.

20 In Figure 4, it will be observed that flange 31 is provided with a bolt hole at 31', and the latter is adapted to receive a lower bolt such as 45, in Figure 1, this bolt being engaged by nut 46, and the bolt being adapted to pass thru the upper end of lower leg 11, at the left of Figure 1. An upper bolt 47 passes thru the upper portion of outer corner plate, and also passes thru the leg member 11 extending upwardly from that plate.

25 In framing the structure, it is built up to a level defined by the four corner plates located opposite each other, and the lower bolts 45 are inserted, and pass thru the leg members 11 which have their upper ends terminating 30 at the middle portions of the corner plate at this level. The upper section or next section of the structure, is then assembled, and the leg members 11 of this section are secured by bolts 47 passing thru the lower ends of 35 these particular elements 11. It should be stated that the upper bolt 47 passes thru an aperture 47', in Figure 3, so positioned that the nut for that bolt will be above the inner corner plate, whereas bolt 45 passes thru aperture 31' of Figure 4.

40 By the use of this construction, all strains to which a derrick is subjected, owing to wind pressure, and all strains resulting from use under normal conditions, and under extraordinary conditions, are resisted in a maximum degree. The particular type of lock 45 between the tubular metallic girts and the corner plates aids materially in effecting the result stated.

45 In the upper portion of Figure 1, and in Figure 2, I have shown a particular type of corner plate and corner box, including the outer plate of angle form and including the flanges 13', the latter having upward extensions 13', each provided with an aperture such as 21' for engagement by hook portions of transverse tie members or braces 55 adapted to be placed under tension by turnbuckle 56. Shoulders are formed at 57, and the trans-

50 leg members 10, or upon plates carried by said upper ends. Transverse girts 59 are locked to the upper box structure including the inner and outer corner plates of Figure 2, the construction illustrated in this view 70 last named being similar in many respects to the construction of Figures 3, 4 and 5, but the outer corner plate of 52 is especially designed for use at the top of the derrick.

It should be added that the shoulders 60 75 adjacent to the slots forming the hook portions of the metallic girts are at an angle, conforming to the angle of inclination of the legs of the derrick. The inner angle plate is slightly under size and provides play permitting the firm clamping of the plates on the legs when the nuts are screwed up.

80 The adaptability of this corner plate or corner box to use with wooden girts, is an important feature, and in Figure 7, the 85 wooden girt 60 is secured by bolts 61 and 63, passing thru the flange of the outer corner plate, the end of the wooden girt, and the end of plate 64 abutting the inner corner plate, and being cut away at an angle conforming 90 with the angle of inclination of the derrick. Plates 64 may be separately secured to the ends of girts 60, and the construction here disclosed provides the rigidity already referred to in connection with the use of the 95 metallic girt.

Having thus described the invention, what is claimed is:

1. In construction of the class described, 100 an outer corner plate including flanges provided with apertures, an inner corner plate comprising flanges including extensions adapted to pass thru some of the apertures of the outer plates and to be secured to said plates, the corner plates being reversely positioned with reference to each other, and the inner corner plate including a slotted portion providing a shoulder, and a girt having a slotted end portion and engaging said shoulder. 105

110 2. In construction of the class described, an outer corner plate including flanges provided with apertures, an inner corner plate comprising flanges including extensions adapted to pass thru some of the apertures of the outer plates and to be secured to said plates, the corner plates being reversely positioned with reference to each other, and the inner corner plate including a slotted portion providing a shoulder, and a girt having a slotted end portion and engaging said shoulder, the flanges of the outer plate projecting beyond the flanges of the inner plate, and the ends of the girts being flattened adjacent to the projecting portions. 115

120 3. In construction of the class described, an outer corner plate having flanges provided with apertures, an inner corner plate comprising flanges having the end portions thereof abutting the inner surfaces of the flanges 130

first named, the flanges of the inner corner plate being slotted at the edge portions thereof, and girts having slotted end portions forming hooks engaging the slotted portions 5 of the flanges and forming a lock joint between the edges of the slot in the girt and the surface of the flanges.

4. In construction of the class described, an outer corner plate having flanges provided 10 with apertures, an inner corner plate comprising flanges having the end portions thereof abutting the inner surfaces of the flanges first named, the flanges of the inner corner plate being slotted at the edge portions thereof, and girts having slotted end portions forming a 15 lock joint between the edges of the slot in the girt and the surface of the flanges, and the walls adjacent to the slotted portion

of the girt being cut to form a surface deflected with reference to the longitudinal axis 20 of said girt.

5. In construction of the class described, an outer corner plate having flanges provided with apertures, an inner corner plate comprising flanges having the end portions thereof 25 abutting the inner surfaces of the flanges first named, the flanges of the inner corner plate being slotted at the edge portions thereof, and girts having slotted end portions forming a lock joint between the edges of the slot in 30 the girt and the surface of the flanges, the flanges of the outer plate including upward extensions adapted to be secured to the upper transverse elements of a derrick.

In testimony whereof I affix my signature.

CHARLES W. LYNCH.
